UNITED STATES PATENT OFFICE.

KARL ZIPERNOWSKY AND MAXIMILIAN DÉRI, OF BUDA-PESTH, AUSTRIA-HUNGARY.

DYNAMO-ELECTRIC MACHINE.

SPECIFICATION forming part of Letters Patent No. 284,110, dated August 28, 1883.

Application filed November 23, 1882. (No model.)

To all whom it may concern:

Be it known that we, KARL ZIPERNOWSKY and MAXIMILIAN DÉRI, subjects of the Emperor of Austria-Hungary, residing at the city 5 of Buda-Pesth, Empire of Austria-Hungary, have invented certain new and useful Improvements in Dynamo-Electric Machines, of which the following is a specification.

This invention relates to an electrical machine combining the functions of a dynamo-machine and a machine with alternating currents, since it generates alternating currents, and is so arranged as to be able to supply its inducing electro-magnets from its own current.

15 Its object is by special methods to excite its own electro-magnets, according to requirements, with continuous or intermittently weaker currents flowing in the same direction, and by a peculiarly solid and effective con-

20 struction of the induction apparatus, in which the currents are generated, and by a secure attachment of its several component parts to furnish a reliable and durable current-producer, which can be adopted for the various 25 requirements of electric lighting. In order to further attain an entire security in the working, especially when incandescent lamps are introduced into the main circuit in parallel arc, a new manner of exciting the electro-

30 magnets by means of differential excitement is applied, which allows the energy of the current to be automatically increased in exactly or proximately that degree as the varying number of incandescent lamps require.

35 It is also to be noticed in this invention that the working-current, which is at times very powerful, is led off from fixed lamps to the field-magnets without commutation, and that by the use of two commutators and two sets of 40 helices around the field-magnets only the currents of one polarity are sent intermittently through a shunt round the field-magnets, while the currents of the opposite polarity are short-circuited in the commutator. The main or 45 working current always remains an alternating one.

In the drawings, Figure 1 is a vertical central section of the machine. Fig. 2 is an end view thereof, partly in section. Fig. 3 is a 50 plan view of an induction-bobbin, parts being broken away. Fig. 4 is a vertical longitudi-

nal section of the same. The remaining figures are details, which will be hereinafter referred to.

Similar letters indicate corresponding parts. 55

The electro-magnets are prismatic iron cores placed radially upon the axle, and wound about with copper wire, as shown in Figs. 1 and 2, so that the space between the cores is most advantageously utilized. The iron cores 60 are re-enforced with the polar plates *p*, and are fastened to the prismatic hub *u* by means of screws passing from without through the polar plates and through the whole body of the core, and are furthermore laterally strengthened and held by metal disks *s*, which disks are perforated or broken through for the admission of ventilating air and the prevention of Foucault currents, (currents generated by reason of proximity to a magnet.) The electro-magnets form, in connection with the axle 65 *w*, a rigid system, which may be rotated by means of the pulley *t*. The wire windings of the electro-magnets are connected behind or next to one another in a continuous series 70 in such a manner that north and south poles must alternately be formed. An even number of magnetic poles is consequently necessary, while the number of induction-bobbins, on the contrary, may be odd, without disturbing the 75 production of utilizable alternating currents.

It is best, if the space permits, to take the number of induction-bobbins equal to that of the magnetic poles, or, if two current-circuits are to be separately led off, twice as great as the 80 number of the latter. The alternation of current is, however, governed by the number of magnetic poles. The induction-cylinder—that is, that part of the machine in which the alternating working-currents are generated—is constructed as follows:

Fig. 3 shows the core of an induction-bobbin. It consists of a cast-iron plate, *a*, curved to form the segment of a circle, so that a number of them may be fitted together to 95 form the cylinder surrounding the field-magnets. On this plate are cast thin ribs *a*², projecting inwardly, running across the plate, and connected to each other only through their common base-plate, *a*. Plate *a* and its ribs are 100 able to rapidly change their magnetic condition by reason of their peculiar form and careful

annealing. The larger spaces between the ribs are filled with wooden blocks or cushions *h*, for the purpose of fastening. To form these cores into bobbins, perforated sheet-metal plates or strips *b*⁴ *b*⁵ are screwed onto the faces over the ribs *a*³, extending beyond them, and between the projecting edges of these plates *b*⁴ *b*⁵ and plate *a* the coiling-space is formed, so that the wire is thus coiled round the ribs and between the projecting edges of the upper plate and the lower interrupted plates, as shown in plan in Fig. 3 and in section in Fig. 4. These plates *b*⁴ *b*⁵ consist of strips separated from each other, in order not to form a continuous conductor, so that no currents can be induced in them, and these plates are attached to the bobbin-cores, as also to the wooden blocks *k*, wedged in between the bobbins, thus guarding against vibrations, which would otherwise cause an undesirable noise of the machine. The bobbins are either wound about with insulated copper wire, or oblong stamped copper plates *o*, slit open at one part, (the same being shown in Fig. 7 in plan view and end view,) are passed over the same, and the plates soldered together at the ends, so as to form a spiral continuous conductor, the separate plates being insulated from one another by asbestos or other paper. A suitable number of these bobbins is formed into a drum or cylinder, and their conductors are combined, either in succession (diagram Fig. 5) or in parallel series, (diagram Fig. 6,) so as to form one or more circuits. After the induction-cylinder has been securely enveloped in paper, a series of wooden rings, *r*, are placed upon it, these rings *r* corresponding with the wooden cushions of the bobbin-core, and similar wooden rings, *r*, are placed around the edges of the induction-cylinder. The intervals *d* between the wooden rings *r* are filled out either with peripherally-wound thin iron wires or with thin iron rings magnetically insulated and having their narrow edges set uppermost. The induction-cylinder is then fastened to the frame *L* of the machine by means of traverses *T*, to which the wooden cushions *h* are fastened by screws passing through the wooden rings *r*, thus hindering the deformation and peripheral displacement of the cylinder or of the several bobbins. It is to be noticed that the cast-iron core of the induction-bobbin is not an indispensable part of the same, but is only intended to increase the inductive effect. Said core can be made of wood, porcelain, and other indifferent bodies.

The arrangement of the current-exciting and current-conducting parts is as follows: The alternating current, arising in the induction-cylinder, branches off on leaving the contact-screws *a*¹ *a*², Fig. 10, passing into the resistances *w*² and to the brushes *b*¹ *b*², from whence it can reach the electro-magnet coils by means of the commutator. (Shown in Fig. 8 in vertical central section, in transverse section, and in plan view developed on a plane.) The drawings show the combination of the parts

of the commutator. The sectors *s*' and *s*² at the periphery of the commutator are at the sides alternately combined with the rings *r*' *r*², while the smaller intermediate sectors, *s*³, remain insulated from both. These latter sectors are alternately either screwed to the ring-shaped insulated pieces *u*' and *u*², or the central ring-shaped piece, *u*², and every sector (*s*' *s*¹ and *s*² *s*³) is connected to form a conductor; but the diametrically-opposite sectors are separated or insulated from one another. The intermediate sectors, *s*³, thus break the contact between the brushes and electro-magnet coils at the moment when the change of current takes place in the machine. The remaining sectors, *s*' *s*², whose number corresponds to the number of the magnetic poles, change the contact with the diametrically-placed brushes *b*' *b*², so that the branch current must turn in the same direction. The resistances of the electro-magnet coils are so chosen that the strength of the shunted currents passing in the same direction corresponds to the desired magnetization.

A modified manner of arrangement is shown in Fig. 11. In this case the object is to shunt the magnetizing-current, which is to flow in one direction only in a portion of the circuit between a connecting-screw and the working-resistances, without hindering the further course of the alternating current. The alternating current passes from the connecting-screw *a*', branches off in front of the brush *b*', and, passing partly through the commutator, partly through the resistance *w*', it is united behind the brush *b*², so as to again form a single current. The commutation in this case is not effected in the customary manner of reversal, but by leading the currents having one direction partly into the shunt, where they flow about the electro-magnets. The currents having the opposite direction, on the other hand, are led on in short circuit through connected parts of the commutator without reaching the electro-magnet wire. In the commutator, short circuit and interruption change as often as the direction of current in the machine. By the application of two current-circuits, which are alternately and severally shunted, a continuous magnetization can also be accomplished.

The construction of the commutator is seen in Fig. 9. The commutator is, in the direction of its width, divided into three parts, of which the middle one contains as many insulated sectors *s*' *s*² as there are magnetic poles, while the other parts form unbroken contact-rings *r*' *r*². A brush, *b*', rubs against one of the rings *r*' or *r*²—that is, against one end of the electro-magnet coil, while the other brush, *b*², must alternately touch the sectors *s*' and *s*²—that is, first one and then the other end of the coil. Consequently the current between the contact-brushes is at one time on short circuit, and then it is sent through the coil of the electro-magnets. The branch current, and with it the magnetic intensity of the poles, can be reg-

ulated by means of the changeable resistance w' ; or, to utilize the energy of the current more economically, a constant utilizable resistance may be put in place of the resistance w' .

5 The two manners of arrangement just described may also be combined in a machine for the purpose of thereby accomplishing an automatic regulation of intensity of the current. This method is especially adapted to 10 the case where the machine has to furnish lights on parallel arc. As seen in Fig. 12, the electro-magnet is wound about with two insulated coils, U' and U^2 , each coil respectively connected with the commutator c' and c^2 . The 15 commutator c^2 allows the alternating current from coil U^2 to periodically pass through it on short circuit, said commutator being in contact with brushes b' b^2 in the manner shown in Fig. 9. From this commutator c^2 also passes 20 a weaker shunt-current, which, flowing through the conductor c , forms a circuit with the lamp-resistances. This current passes through conductors f and g , through the induction-bobbins b^3 , connected together by wire v , and thence 25 through the commutator c' , which commutator is also in contact with brushes b' b^4 . The line xx indicates the axial line about which the commutators and electro-magnets revolve. The letter w^2 designates the lamps. The current 30 flowing through the commutator c' passes in uniform direction into the thin coil U' of the electro-magnets. The currents flowing through the coils U' U^2 have always opposite directions; consequently only the difference of 35 the two currents is effective in exciting the electro-magnets; but since, by increasing the resistance in the outer circuit, (i. e., by cutting off certain lamps,) the stronger of the two currents will be weakened, while the weaker one 40 will be strengthened, the magnetic intensity of the poles will consequently increase or decrease in the same proportion as the number of lamps in the circuit increases or decreases. This method of regulation can also be effected 45 if the magnetizing-coil U^2 receives a constant current from an exterior source—for instance, from a dynamo-machine—while the shunt-current in the counter-coil U' , which receives a uniform direction through the commutator c' , 50 serves for weakening, and consequently regulating, the magnetic intensity. In all cases where the magnetic excitement is to proceed from without, the commutators, Figs. 8 and 9, are so constructed that by means of suitable 55 copper brushes a current can be led to the electro-magnets from without through the contact-rings r' r^2 .

What we claim as new, and desire to secure by Letters Patent, is—

60 1. A sector-bobbin consisting of the segmental plate a , having the projecting ribs

thereon, provided with the two or more interrupted plates b b^4 b^5 , and surrounded by a conductor, substantially as described.

2. A sector-bobbin composed of a zigzag-shaped core, a , provided with wooden blocks h , for the retention of plates b , said core being surrounded by a conductor, substantially as and for the purpose described. 65

3. An induction-cylinder composed of wooden rings r and conductor or iron wire d , and of sector-bobbins having their cores provided with wooden cushions h , said sector-bobbins being connected to the wooden rings r , substantially as and for the purpose set forth. 70

4. A sector-bobbin having a core, a , provided with wooden blocks h k , and metal plates b , attached to said cores a and to said wooden blocks h k , thus securely fastening the said plates b , substantially as and for the purpose set forth. 75

5. A commutator consisting of rings r' r^2 u' u^2 u^3 , sectors s' s^2 , communicating with said rings r' r^2 and sectors s^3 , which serves to break the circuit between sectors s' and s^2 , communicating with said rings u' u^2 u^3 , substantially as and for the purpose set forth. 85

6. In an electric machine, the combination, with the induction-bobbins, of the field-magnets provided with a coil, U^2 , wound in one direction for the primary current, and a coil, U' , wound in the opposite direction for the regulating-current, of the short-circuiting commutator c^2 , communicating with coil U^2 and commutator c' , communicating with coil U' , whereby a current of one polarity only is sent from commutator c^2 and an alternating current from commutator c' , and whereby the intensity of the current is automatically regulated. 95

7. In an electric machine, the combination, with the coils of the induction-bobbin, of the field-magnets provided with a coil, U^2 , wound in one direction for the primary current, and a coil, U' , wound in the opposite direction for the regulating-current, of the short-circuiting commutator c^2 , communicating with coil U' , and commutator c' , communicating with coil U' , whereby a current of one polarity only is sent from commutator c^2 through the coils of the induction-bobbins, and from commutator c' a continuous current, and whereby the intensity of the current is automatically regulated. 105

In testimony whereof we have signed our names to this specification in the presence of 110 two subscribing witnesses.
